[57] CLAIM

The ornamental design for a flexible traffic delineator post, as shown and described.

DESCRIPTION

FIG. 1 is a front perspective view of a flexible traffic delineator post showing our new design;

FIG. 2 is a top plan view thereof, with the bottom plan view being substantially a mirror image;

FIG. 3 is a front elevational view thereof;

FIG. 4 is a rear elevational view thereof; and

FIG. 5 is a right side elevational view thereof, with the left side being substantially a mirror image.
